UNITED STATES PATENT OFFICE.

FRANK W. MERRICK, OF BOSTON, MASSACHUSETTS.

MACHINE FOR EDGE-FINISHING STRIPS OF MATERIAL.

1,323,371.

Specification of Letters Patent.

Patented Dec. 2, 1919.

Application filed March 19, 1917. Serial No. 155,693.

To all whom it may concern:

Be it known that I, FRANK W. MERRICK, a citizen of the United States, residing at Boston, in the county of Suffolk, State of Massachusetts, have invented a certain new and useful Improvement in Machines for Edge-Finishing Strips of Material, of which the following is a specification, reference being had therein to the accompanying drawings.

The invention consists in devices of novel and improved character which are chiefly designed for use in applying a finishing, coloring, or coloring and finishing, solution or preparation to strips of material, usually strips of thin and flexible material. An important use of the features of the invention is in the treatment of stay-strips and the like. These strips are narrow, and usually are made of leather but in some cases are made of other material. The said features are applicable in the finishing of strips of paper, and are not in all cases restricted to use in connection with narrow strips. They lend themselves, however, with especial advantage to use in machines adapted for the finishing of narrow strips. Devices embodying the said features are adapted to be employed to apply the solution or preparation to one or both of the edges of a strip, and if desired to one surface also of the strip.

A leading aim of the invention is to provide for applying solution or preparation to one or both edges of a strip but keep the face of the strip clean and entirely free from the solution or preparation.

The invention, broadly stated, consists in the combination with a moving carrier, which may be a wallower-roll, or combined with one, and which preferably serves also as a feed-roll for the strip that is operated upon, of one or more scrapers or wipers by which solution or preparation coating the said carrier is displaced transversely toward the corresponding edge or edges of a traveling strip, to thereby treat the said edge or edges. It includes a primary wiper by which the coating may be removed from that portion of the moving carrier which is touched by the surface of the traveling strip, in case it is desired that such surface shall remain free from the solution or preparation. It includes an improved doctor 55 for securing uniformity transversely in the

thickness of the coating carried around upon the surface of the carrier.

An illustrative embodiment of the features of the invention in a machine for treating a narrow stay-strip is shown in the drawings, in which latter,—

Figure 1 is a side elevation of the said machine.

Fig. 2 is a plan view thereof.

Fig. 3 is a view thereof in vertical section on line 3—3 of Fig. 2.

Fig. 4 is a detail view, in section, showing the manner in which in the said machine the scrapers or wipers are mounted adjustably.

Fig. 5 is a plan view of the doctor.

Fig. 6 is an end view thereof.

In the drawings, a stay-strip *a* is represented as passing through the machine. 1 is a moving carrier, in this instance constituted by a wallower-roll, the lower portion of which dips into a pan or container 2 that holds the solution or preparation 3 (Fig. 3) to be applied to the said strip. By the rotation of the wallower the coating of solution or preparation adhering to the surface thereof is carried around therewith. A doctor 4 determines the thickness of the said coating, and thereby determines the amount of solution or preparation that is supplied for application to the strip. The latter goes through a strip-guide 5 having its delivery-end or nose located between the periphery of the carrier and that of a presser-roll 6, and close to the nip or point of closest approach of the said rolls. The strip in leaving the guide passes between the two rolls, it being held by the presser-roll against the periphery of the carrier. The carrier or wallower is utilized as a feed-roll, it and the presser-roll constituting a pair of feed-rolls which grip the strip alongside the place of application of the solution or preparation to the strip, and serve to feed the strip through the devices and past the said place.

In the machine shown in the drawings the presser-roll is driven through power-connections that are combined therewith, as explained later herein, and as it rotates it operates through engagement with the strip to feed the latter through the machine, the carrier or wallower being caused to turn as a result of the engagement of the strip with the surface of the carrier or wallower.

According to one portion of the inven-

tion, if solution or preparation is to be applied to the strip-surface which makes contact with the wallower periphery, the corresponding portion of such periphery is 5 permitted to remain charged or coated with solution or preparation until it transfers the same to the said strip-surface. If, however, such strip-surface is to remain uncoated or uncolored, the said portion of the 10 said periphery is wiped clean before the strip touches such portion. To enable either result to be attained in practice as desired, the illustrated machine is furnished with a wiper which may be brought into 15 action or placed out of action at will. This wiper is constituted by the underside of the nose of the strip-guide 5. The said underside is shaped to fit smoothly and snugly against the periphery of the wallower-roll, 20 and in width corresponds properly with that of the strip. The guide is adjustable, as explained later herein, so as to enable the said underside thereof to be held out of contact with the periphery of the wallower, or 25 in contact therewith, as desired. If the said underside is held out of contact with the periphery of the wallower the coating on such periphery will be left undisturbed and the strip-surface which comes in contact 30 with the wallower will receive the said coating. If the underside of the guide is held in contact with the surface of the wallower, that portion of the periphery of the wallower with which it makes contact will have 35 the coating wiped therefrom so that none will be applied to the said surface of the strip.

In accordance with another portion of the invention, for the purpose of applying the 40 solution or preparation to one or both of the edges of the strip, the machine is furnished with side-scrappers or wipers 7, 7. These are arranged to make contact with the periphery of the wallower-roll 1 at opposite 45 sides of the point at which the presser-roll 6 makes contact with the strip *a*, as well as in advance of such point, and their acting portions converge toward each other and the strip between them. The undersides of the 50 said acting portions are curved to fit the curved periphery of the wallower. The transverse inclination or convergence of the side-scrappers or wipers toward each other operates to deflect inwardly toward and 55 against the edges of the strip those portions of coating which are carried by the portions of the wallower-periphery with which the side-scrappers or wipers make contact. The side-scrappers or wipers 7, 7, may touch the 60 edges of the strip externally, but the best results are attained in practice when they do not actually make contact therewith but are separated by a narrow space therefrom. The said scrapers or wipers are mounted in 65 manner providing for adjustment of the

same widthwise of the strip toward and from each other, to suit different widths of strip. A convenient means of mounting and adjusting them is shown in the drawings (see more particularly Fig. 4) in which the 70 stem-portion of each scraper or wiper is attached by means of a screw 8 to a slide-piece 9, the two slides 9, 9, being fitted one on top of the other within a transverse groove 10 in the upper portion of a stand 75 or bracket 11, and being fixed in place by means of a clamping screw 12, the stem of which passes through longitudinal slots 13, 13, Figs. 2 and 4, in the said slides, and the threaded portion of the said stem being engaged in a threaded hole in the top of the stand or bracket 11. This mode of mounting the slides enables them to be adjusted transversely, as may be required in order to locate the scrapers or wipers at the proper 80 distance apart.

In practice, one only of the side-scrappers or wipers will be employed in case it is desired to treat one edge only of a strip.

The manner and means of supporting the 90 various parts, and rotating the rolls, may vary in practice. In the drawings the wallower-roll is shown journaled in open bearings in connection with the opposite side-pieces 15, 15, of a swing-frame that is hung 95 at one end upon a shaft 16 that is supported by bearings in connection with a fixed stand 17. The opposite end of the swing-frame is provided with a contact-screw 18 resting by its lower end upon a block 19, so 100 that by the adjustment of the said screw the swing-frame may be adjusted vertically to thereby regulate the extent to which the lower portion of the wallower-roll dips into the pan or other container 2 and into the 105 solution 3 therein. A stripper 20 carried by the swing-frame, and having its acting end close to the periphery of the wallower-roll at the delivery-side of the nip between the two rolls, prevents the strip *a* from 110 clinging to the wallower-roll and being carried around with the latter in its revolution.

The presser-roll 6, in this instance, is fixed upon a shaft 21 mounted in a bearing 22 provided upon an arm 23. The said arm 115 is furnished with an elongated hub-portion 23^a that is mounted between center-screws 24, 24, in connection with uprights 25, 25, upon the swing-frame. This mode of mounting the said arm between center-screws at a considerable distance apart prevents twisting of the arm transversely, and insures flat contact of the periphery of the presser-roll with the strip *a*. The pressure 120 of the pressure-roll is produced by the tension of a contracting spiral spring 26 having one end thereof engaged with a side-piece of the swing-frame 15 and the other with the arm 23.

The illustrated driving means of the 130

- presser-roll 6 comprises a spur-pinion 27 fixed upon the shaft 21 of said roll, an idle-gear 28 with which pinion 27 engages, mounted to turn upon the plain outer portion of one of the center-screws 24, and a spur-gear 29 with which idle-gear 28 also engages, fixed upon the shaft 16, which shaft is rotated by suitable actuating means (not shown) in connection therewith.
10. The width of the presser-roll is less than that of the strip *a* that is operated upon, in order that the solution or preparation that is deflected by the side-scrapers or wipers transversely toward and against the edges 15 of the strip may not touch the presser-roll. This insures against any of the solution or preparation appearing on the face of the strip. If the solution or preparation should touch the presser-roll it would in consequence 20 be caused to show on said face. To enable the machine to be adapted to operate upon different widths of strips, the presser-roll is mounted detachably upon shaft 21 between a shoulder 21^a of said shaft and a nut 21^b which screws upon the shaft.
- The strip-guide 5 is mounted in place by means of a pin 61, Fig. 3, projecting downward from the stem of the guide and entering a vertical socket in a block 62 carried 30 by a yoke 63 that is hung upon reduced end-ports of the hub 23^a of swing-arm 23. A clamping-screw 621 passing through the said block engages with pin 61 to prevent the guide and pin from rising relative to the 35 block. The guide may be removed at will by loosening the screw 621 and lifting the guide so as to withdraw the pin 61 from the said socket. By means of a contracting spiral spring 64 having one end thereof engaged with an arm 65 projecting downward from the yoke 63 and the other end thereof engaged with a cross-rod 66 of the swing-frame 15, the guide is held down in working position. Referring now to the 40 means of adjusting the guide to secure the special results which have been mentioned: When it is desired that the underside of the nose of the guide shall act as a wiper, as when solution or preparation is not to be applied to the under surface of the strip, the spring is permitted to keep the nose pressed in yielding manner against the periphery of the wallower. When it is desired that the nose shall not act as a wiper, 45 a stop-screw 651, Figs. 1 and 3, carried by the arm 65, is adjusted to engage with the adjacent upright 25 of the swing-frame 15 so as to limit the approach of the nose toward the wallower periphery and prevent it 50 from touching the latter. By reverse adjustment of screw 651 the nose may be permitted to touch the said periphery again.
- The doctor 4 is carried by a rock-bar 51 which is mounted pivotally upon a cross-pin 52 carried by the uprights 25, 25, of the 55 swing-frame 15. It occupies an inclined position, with its elevated acting end resting upon the upper portion of the periphery of the wallower-roll in advance of the guide 5. An adjusting-screw 53 working through a threaded hole tapped in the forwardly-projecting arm 54 of said doctor engages by its lower end with cross-rod 66 of the swing-frame. A contracting spiral spring 55, having one end engaged with arm 54 and the other with a cross-pin 56 carried by swing-frame 15, acts in opposition to the adjusting-screw 53, with a tendency to move the acting portion of the doctor away from the periphery of the wallower. By means of the adjusting screw the acting end of the doctor may be caused to bear with the required pressure against the wallower-periphery.
- It is difficult to secure uniformity in the 85 coating, transversely of the wallower-roll, when an ordinary doctor is employed. I secure the desired uniformity by means of the special construction of doctor that is shown in the drawings, forming a feature of the 90 invention. In the case of such construction, a main acting portion extends across the face of the wallower-roll and is adapted to act in usual manner in conjunction therewith. Ears 57, 57, projecting from the said 95 main portion at the sides of the wallower-roll, remove from said sides the portions of solution or preparation finding their way thereto. A supplemental acting portion, 58, is located beneath the main acting portion. 100 The said supplemental acting portion has its engaging end located in a recess in the under side of the main acting portion at one side of the middle of the width of the said main portion, as shown in Fig. 6, and is 105 about one-half the width of the main portion. It is constituted by a strip of spring material that is connected by one end thereof with the main portion beyond the cross-pin 52. An adjusting-screw 59 applied to the 110 main portion of the doctor engages by its end with the said strip. By adjustment of the said screw, the engaging end of the supplemental acting portion may be caused to bear more or less effectually for wiping 115 purposes so as to secure the desired uniformity of wiping action across the face of the wallower-roll.
- What is claimed as the invention is:—
1. The combination with a moving carrier, of a scraper or wiper by which solution or preparation coating the surface of said carrier is displaced transversely toward an edge of a traveling strip of material, to thereby treat the said edges. 120
  2. The combination with a moving carrier and a presser co-operating therewith to feed along a strip passing between them, of a scraper or wiper by which solution or preparation coating the surface of said carrier is 125
- 65 52 carried by the uprights 25, 25, of the 130

displaced transversely toward an edge of the strip to thereby treat the said edge.

3. The combination with a moving carrier and a presser coöperating therewith to feed along a strip passing between them, said presser narrower than the said strip so that a marginal portion of the strip projects laterally of the presser, of a scraper or wiper by which solution or preparation coating the surface of said carrier is displaced transversely toward the projecting edge of the strip to thereby treat the said edge.

10 4. The combination with a moving carrier, of opposite scrapers or wipers between which 15 a strip of material passes and by which solution or preparation coating the surface of said carrier is displaced transversely toward the edges of the said strip, to thereby treat the said edges.

20 5. The combination with a moving carrier, and a presser coöperating therewith to feed along a strip passing between them, of side scrapers or wipers at opposite sides of the path of said strip and by which solution or 25 preparation coating the surface of the carrier is displaced transversely toward the edges of the said strip to thereby treat such edges.

30 6. The combination with a moving carrier, and a presser coöperating therewith to feed along a strip passing between them, said presser narrower than the strip so that marginal portions of the latter project at opposite sides of the presser, of side-scrapers or 35 wipers at opposite sides of the presser and by which solution or preparation coating the surface of the carrier is displaced transversely toward the edges of the strip to thereby treat such edges.

40 7. The combination with a rotatable wallower-roll, of a scraper or wiper by which the solution or preparation coating the surface of said wallower-roll is displaced transversely toward an edge of a traveling 45 strip of material, to thereby treat the said edge.

8. The combination with a wallower-roll, and a presser coöperating therewith to feed along a strip passing between them, of a 50 side-scraper or wiper by which solution or preparation coating the surface of the wallower-roll is displaced transversely toward an edge of said strip to thereby treat such edge.

55 9. The combination with a wallower-roll, and a presser coöperating therewith to feed along a strip passing between them, said presser narrower than said strip so that a marginal portion of the strip projects laterally of the presser, of a side-scraper or 60 wiper by which solution or preparation coating the surface of the wallower-roll is displaced transversely toward the projecting edge of the strip to thereby treat the latter.

10. The combination with a rotatable wallower-roll, of opposite scrapers or wipers between which a strip of material passes and by which solution or preparation coating the surface of said wallower-roll is displaced transversely toward the edges of the said 70 strip, to thereby treat the said edges.

11. The combination with a wallower-roll, and a presser coöperating therewith to feed along a strip passing between them, of opposite side-scrapers or wipers by which 75 solution or preparation coating the surface of the carrier is displaced transversely toward the edges of the strip to thereby treat both of said edges.

12. The combination with a wallower-roll, and a presser coöperating therewith to feed along a strip passing between them, said presser narrower than said strip so that marginal portions of the latter project at opposite sides of the presser, of opposite side-scrapers or wipers by which solution or preparation coating the surface of the carrier is displaced transversely toward the edges of the strip to thereby treat both of 80 said edges.

90 13. The combination with a moving carrier adapted to hold a coating of solution or preparation, of a wiper for removing such coating from the portion of said carrier which contacts with a traveling strip of 95 material, and a scraper or wiper by which the solution or preparation remaining upon an adjoining portion of the carrier is displaced transversely toward an edge of the said strip, to thereby treat the said edge. 100

14. The combination with a moving carrier adapted to hold a coating of solution or preparation, and a presser coöperating therewith to feed along a strip passing between them, of a wiper for removing such coating from the portion of such carrier which contacts with the traveling strip of material, and a scraper or wiper by which solution or preparation remaining upon an adjoining portion of the carrier is displaced 105 transversely toward an edge of the strip to thereby treat such edge. 110

15. The combination with a rotatable wallower-roll, of a wiper which removes the coating of solution or preparation from that portion of the surface of the wallower-roll which contacts with the surface of a strip traveling past the wallower-roll, and a scraper or wiper by which the solution or preparation upon an adjoining coated portion of the wallower-roll is displaced transversely against an edge of the strip, to thereby treat the said edge. 115

16. The combination with a rotatable wallower-roll adapted to hold a coating of solution or preparation, and a presser coöperating therewith to feed along a strip passing between them, of a wiper for removing 120

- such coating from the portion of the wallower-roll which contact with the traveling strip of material, and a scraper or wiper by which the solution or preparation remaining upon an adjoining portion of the carrier is displaced transversely toward an edge of the strip to thereby treat such edge. 17. The combination with a moving carrier adapted to hold a coating of solution or preparation, of a wiper for removing such coating from an intermediate portion of the said carrier, and opposite scrapers or wipers by which solution or preparation remaining upon adjoining portions of the carrier is displaced transversely toward the opposite edges of a strip of material traveling over the uncoated portion of the carrier, to thereby treat the said edges. 18. The combination with a moving carrier adapted to hold a coating of solution or preparation, and a presser coöperating therewith to feed along a strip passing between them, of a wiper for removing such coating from the portion of such carrier which contacts with the traveling strip of material, and opposite scrapers or wipers by which solution or preparation upon adjoining portions of the carrier is displaced transversely toward the opposite edges of the strip to thereby treat such edges. 19. The combination with a wallower-roll, of a wiper which removes the coating of solution or preparation from an intermediate portion of the surface of the wallower-roll, and opposite scrapers or wipers by which the solution or preparation remaining upon adjoining coated portions of the wallower-roll is displaced transversely toward and against the opposite edges of a strip traveling over the intermediate portion of the wallower-roll, to thereby treat the said edges. 20. The combination with a wallower-roll, and a presser coöperating therewith to feed along a strip passing between them, of a wiper for removing such coating from the portion of the wallower-roll which contacts with the strip, and opposite scrapers or wipers by which solution or preparation upon adjoining portions of the wallower-roll is displaced transversely toward the opposite edges of the strip to thereby treat such edges. 21. The combination with a moving carrier adapted to hold a coating of solution or preparation, of a strip-guide having a wiper for removing such coating from the portion of such carrier which contacts with the traveling strip of material, and a scraper or wiper by which solution or preparation remaining upon an adjoining portion of the carrier is displaced transversely toward an edge of the strip to thereby treat such edge. 22. The combination with a moving carrier adapted to hold a coating of solution or preparation, and a presser coöperating therewith to feed along a strip passing between them, of a strip-guide having a wiper for removing such coating from the portion of such carrier which contacts with the traveling strip of material, and a scraper or wiper by which solution or preparation remaining upon an adjoining portion of the carrier is displaced transversely toward an edge of the strip to thereby treat such edge. 23. The combination with a rotatable wallower, of a strip-guide having a wiper for removing the coating of solution or preparation from the portion of the wallower which contacts with the traveling strip of material, and a side-scraper or wiper by which solution or preparation remaining upon an adjoining portion of the wallower is displaced transversely toward an edge of the strip to thereby treat such edge. 24. The combination with a rotatable wallower, and a presser coöperating therewith to feed along a strip passing between them, of a strip-guide having a wiper for removing the coating of solution or preparation from the portion of the wallower which contacts with the traveling strip of material, and a side-scraper or wiper by which solution or preparation remaining upon an adjoining portion of the wallower is displaced transversely toward an edge of the strip to thereby treat such edge. 25. The combination with a moving carrier adapted to hold a coating of solution or preparation, of a strip-guide having a wiper for removing such coating from the portion of such carrier which contacts with the traveling strip of material, and opposite side-scrapers or wipers by which solution or preparation upon adjoining portions of the carrier is displaced transversely toward the opposite edges of the strip to thereby treat such edges. 26. The combination with a rotatable wallower, of a strip-guide having a wiper for removing the coating of solution or preparation from the portion of the wallower which contacts with the traveling strip of material, and opposite side-scrapers or wipers by which solution or preparation remaining upon adjoining portions of the wallower is displaced transversely toward the two edges of the strip to thereby treat such edges. 27. The combination with a moving carrier adapted to hold a coating of solution or preparation, and a presser coöperating therewith to feed along a strip of material passing between them, of a strip-guide having a wiper for removing such coating from the portion of such carrier which contacts with the traveling strip of material, and opposite side-scrapers or wipers by which solution or preparation upon adjoining portions of

the carrier is displaced transversely toward the opposite edges of the strip to thereby treat such edges.

28. The combination with a rotatable wallower, and a presser coöperating therewith to feed along a strip of material passing between them, of a strip-guide having a wiper for removing the coating of solution or preparation from the portion of the wallower 5 lower which contacts with the traveling strip of material, and opposite side-scrapers or wipers by which solution or preparation remaining upon adjoining portions of the wallower is displaced transversely toward the two edges of the strip to thereby treat such edges.

29. The combination with a moving carrier adapted to hold a coating of solution or preparation, of a strip-guide having a wiper for removing such coating from the portion 20 of such carrier which contacts with the traveling strip of material, and also adjustable into working positions either in or out of contact with the carrier, and a scraper or 25 wiper by which solution or preparation remaining upon an adjoining portion of the carrier is displaced transversely toward an edge of the strip to thereby treat such edge.

30. The combination with a moving carrier adapted to hold a coating of solution or preparation, and a presser coöperating therewith to feed along a strip passing between them, of a strip-guide having a wiper for removing such coating from the portion of 35 such carrier which contacts with the traveling strip of material, and also adjustable into working positions either in or out of contact with the carrier, and a scraper or 40 wiper by which solution or preparation remaining upon an adjoining portion of the carrier is displaced transversely toward an edge of the strip to thereby treat such edge.

31. The combination with a rotatable wallower, of a strip-guide having a wiper for 45 removing the coating of solution or preparation from the portion of the wallower which contacts with the traveling strip of material, and also adjustable into working positions either in or out of contact with the carrier, and a side-scraper or wiper by which 50 solution or preparation remaining upon an adjoining portion of the wallower is displaced transversely toward an edge of the strip to thereby treat such edge.

55. 32. The combination with a rotatable wallower, and a presser coöperating therewith to feed along a strip passing between them, of a strip-guide having a wiper for removing the coating of solution or preparation 60 from the portion of the wallower which contacts with the traveling strip of material, and also adjustable into working positions either in or out of contact with the carrier, and a side-scraper or wiper by 65 which solution or preparation remaining

upon an adjoining portion of the wallower is displaced transversely toward an edge of the strip to thereby treat such edge.

33. The combination with a moving carrier adapted to hold a coating of solution or preparation, of a strip-guide having a wiper for removing such coating from the portion of such carrier which contacts with the traveling strip of material, and also adjustable into working positions either in or out of 75 contact with the carrier, and opposite side-scrapers or wipers by which solution or preparation upon adjoining portions of the carrier is displaced transversely toward the opposite edges of the strip to thereby treat 80 such edges.

34. The combination with a rotatable wallower, of a strip-guide having a wiper for removing the coating of solution or preparation from the portion of the wallower 85 which contacts with the traveling strip of material, and also adjustable into working positions either in or out of contact with the carrier, and opposite side-scrapers or wipers by which solution or preparation remaining 90 upon adjoining portions of the wallower is displaced transversely toward the two edges of the strip to thereby treat such edges.

35. The combination with a moving carrier adapted to hold a coating of solution 95 or preparation, and a presser coöperating therewith to feed along a strip of material passing between them, of a strip-guide having a wiper for removing such coating from the portion of such carrier which contacts 10 with the traveling strip of material, and also adjustable into working positions either in or out of contact with the carrier, and opposite side-scrapers or wipers by which 10 solution or preparation upon adjoining portions of the carrier is displaced transversely toward the opposite edges of the strip to thereby treat such edges.

36. The combination with a rotatable wallower, and a presser coöperating therewith 11 to feed along a strip of material passing between them, of a strip-guide having a wiper for removing the coating of solution or preparation from the portion of the wallower which contacts with the traveling 11 strip of material, and also adjustable into working positions either in or out of contact with the carrier, and opposite side-scrapers or wipers by which solution or preparation remaining upon adjoining portions of the 1 wallower is displaced transversely toward the two edges of the strip to thereby treat such edges.

37. The combination with a wallower 1 which transfers a coating of solution or the like, and means for supplying said coating to said wallower, of a doctor having relatively movable working members acting upon adjoining sections of the surface of the wallower, and means for adjusting the 1

relative effect of said members in securing the required thickness of coating upon said wallower.

38. The combination with a wallower which transfers a coating of solution or the like, and means for supplying said coating to said wallower, of a doctor having relatively movable working members acting upon adjoining sections of the surface of the wallower, means for adjusting the doctor as a whole to regulate its action, and means for adjusting the relative effect of said members in securing the required thickness of coating upon said wallower.
39. The combination with a wallower which transfers a coating of solution or the like, and means for supplying said coating to said wallower, of a doctor having a primary and a secondary portion, means engaging said primary portion for adjustment

of the doctor as a unit, and means for relative adjustment of said secondary portion upon the primary portion.

40. The combination with a wallower which transfers a coating of solution or the like, and means for supplying said coating to said wallower, of a doctor comprising a primary pivotally-hung portion and a secondary portion carried thereby, means for adjustment of the doctor as a unit upon its pivotal mounting, and means for adjusting said secondary portion relative to the main portion, to vary the action of said secondary portion.

In testimony whereof I affix my signature in presence of two witnesses.
